UNITED STATES PATENT OFFICE.

WINFIELD E. HINSDALE, OF TRENTON, NEW JERSEY, ASSIGNOR TO TRENTON POTTERIES COMPANY, OF TRENTON, NEW JERSEY, A CORPORATION OF NEW JERSEY.

STANDARD OR SUPPORT FOR LAVATORIES AND THE LIKE.

1,284,677.

Specification of Letters Patent. Patented Nov. 12, 1918.

Application filed October 10, 1917. Serial No. 195,766.

To all whom it may concern:

Be it known that I, WINFIELD E. HINSDALE, a citizen of the United States, residing at Trenton, in the county of Mercer and State of New Jersey, have invented certain new and useful Improvements in Standards or Supports for Lavatories and the like, of which the following is a specification.

This invention pertains to an improved standard or support for lavatories, wash sinks and similar fixtures, and has for its main object the production of a standard which is at once simple and strong and which will lend itself to ready and complete installation of lavatories or the like in a battery or line.

A further object resides in so constructing the structure that the supports for the lavatories underlie the same whereby a minimum surface is exposed and the lodgment of dirt is to a great extent prevented.

The structure forming the basis of the invention is designed more particularly for use in factory wash rooms, department store toilets or other places of like character. Heretofore, more or less cumbersome cast iron frames have been used for this purpose, or pipe racks with standards to the floor have been erected to support the fixture.

Such structures by reason of their bulky nature have detracted largely from the merit of the complete installation besides taking up space beneath the fixtures proper and interfering with the plumbing lines with a consequent greater cost for installation.

The present structure while being strong is light in appearance, and offers no obstruction to the plumbing lines. Moreover, it may be said to be composed of a series of unit elements, few in number, which lend themselves to the ready assembling at the place of use for the installation of a short or extended range of lavatories. Again by reason of the unit system employed, the parts may be made up in large quantities and stored away ready for use.

Several arrangements or embodiments of the invention are illustrated in the annexed drawings, wherein:

Figure 1 is a perspective view of a support constructed in accordance with my invention;

Fig. 2 a transverse vertical section on the line II—II of Fig. 1;

55

Fig. 3 a detail perspective view of the top or head of one of the standards with the two bracket base plates;

Fig. 4 a sectional view illustrating the manner in which the standards are tied together;

Fig. 5 a front elevation of a complete structure with two lavatories in place;

Fig. 6 a perspective view showing a modified form of bracket secured to the standard;

65

Fig. 7 a similar view showing the invention as it is adapted for use where the fixtures are placed adjacent a wall; and

Fig. 8 a detail perspective view of the head of one of the standards.

70

Referring first to the construction shown in Figs. 1 to 4, 1 denotes the standards, three being shown, each of which in the form illustrated comprises two side bars or elements which merge at the upper portion of the standard and from which arises a head piece 2. The lower portions of the side elements are preferably connected by a cross piece as shown and suitable feet are provided. In other words, the standard may take any suitable form so long as it is provided with the head piece 2.

The head is rectangular and the two oppositely disposed vertical front and rear faces 3—3, extend upwardly from a ledge or shoulder 4 formed upon the standard 1.

Said faces 3 are provided with alining bolt holes 5, two in each being shown. A threaded opening 6 is provided in the top of the head.

In the arrangement shown in Fig. 1 three standards are employed and to connect said standards and to hold them in spaced relation the connecting devices shown in detail in Fig. 4 will preferably be employed. 95 Heretofore in structures of similar character tie rods, carrying sections of pipe used as spacers between the legs or supports have commonly been employed but such arrangement necessitates the pipe being cut to accurate length and the rods ordinarily extended from end to end of the supporting rack. Such arrangement has several disadvantages and the present construction is superior in that the rods are in sections and do not have to be cut to an absolute accurate

90

95

100

105

length; moreover, any one section of the structure may be removed without disturbing the adjacent section.

As will be seen the webs of the standards 5 1 are bored and threaded to each side of and preferably at a slight distance from the head, and through such openings are passed threaded nipples, as 7. Onto said nipples are screwed socket pieces 8, bearing against 10 the opposite faces of the web of the standard, and thus securing the nipples and sockets firmly in place. The outer portions of the bore of such sockets are left plain and stay rods 9 are passed into such un- 15 threaded portions of the sockets and are held in place therein by set-screws 10. Nuts 11 will preferably be screwed upon the ends of the nipples which protrude beyond the webs of the outermost standards, thereby securing 20 such nipples and the attached sockets firmly in place.

With this construction it will at once be seen that relatively short rods may be employed and that the rods may be readily positioned and secured and as readily removed and that those between any two standards may be removed without disturbing the others.

Brackets 12 formed to bear directly 30 against the opposite faces 3 (of the outermost pair of standards) and to rest upon the shoulders 4 are secured in place by bolts 13 which pass through the brackets and through the holes 5 in the head. Each 35 bracket will preferably be formed with an elongated opening 14 through which bolts may pass for securing the lavatory or basin 15, Fig. 5, in place.

Secured to the head of the intermediate or 40 central standard is a pair of bracket supports or base plates, shown in detail in Fig. 3. Each support comprises a single casting having a central vertically disposed socket or half hub section 16 of a size to embrace 45 one half of the head and to rest upon the adjacent shoulder 4. Extending laterally from each side of the hub and so spaced that the outer face thereof stands in alinement with the outer face 3 of the head 2 50 when the parts are placed, is a plate 17 which at its outer end is formed with an inturned wing or flange 18. A pair of longitudinally disposed slots or openings 19 is formed in each plate 17. Said bracket supports 55 are firmly secured in place upon the head by bolts 20 which pass through the central portion of each support and the openings 5 formed in the head.

Brackets 12 of the same form as above 60 described are secured in opposite pairs to said bracket supports or more specifically plates 17 thereof by bolts 21. By providing the elongated slots 19 said brackets may be adjusted laterally toward or from the 65 outermost brackets so that the basins or lav-

atories may be readily secured in place without straining any of the parts; such arrangement likewise leaves a clear space between adjoining lavatories.

The construction as above outlined admits 70 of the placement of any number of lavatories in double line and likewise affords a supporting structure which in no wise interferes with the running of the necessary water supply and drain pipes. 75

In Fig. 6 the same general arrangement of standards is shown together with the central bracket support and the parts are similarly lettered. The supporting brackets are however different in form and the tie 80 rods are omitted. The brackets in this instance are substantially U-shaped in outline and the body is denoted by 22. An arm or plate 23 extends upwardly from each bracket and said plates are bolted to the head and 85 the bracket support and serve to tie the standards together doing away with the necessity of the tie rods. This modification of the bracket is designed especially for use with deep apron lavatories. 90

In this figure a pipe support 24 is shown attached to one of the heads 2. This support is pierced by an opening 25 of sufficient size to allow the insertion of the usual vent pipe on usual drainage or pitch lines and is 95 likewise provided with two smaller openings 26, 27 for the usual cold and hot water pipes, while means for locking the pipe passing through 27, is provided in set screw 28.

In Figs. 7 and 8 an adaptation of the invention for use in connection with a single row of lavatories to be placed against a wall is illustrated.

The standards 1^a in this instance lie flat against the wall and screws 29, Fig. 8, passing 105 through the head attach it to the wall. The foot piece 15 of each standard is also preferably secured to the floor and brackets 12, as under the first described structure, are employed.

By reason of the fact that the foot piece of each standard extends outwardly on the floor several inches it will be seen that a superimposed load on the brackets in order to draw the standards from the wall must be great enough to first cause the standards to lift on its foot enough to effect a shearing of the screws attaching the heads to the wall structure itself, a strain not likely in practice. The purpose of this fixture is to 115 support a battery of lavatories on the wall face without protruding legs but still to carry the weight to the floor which cannot be done with an ordinary wall bracket. 120

It will now be noticed that the brackets 125 in all cases at the ends of the battery lines are and must be under the lavatories and therefore their upper faces are hidden from view.

If similar brackets were attached directly 130

to the heads of the intermediate standards, they would of necessity have to be widened out to support the adjoining lavatories, in which case the exposed upper face of the bracket, between the adjoining lavatories, would form a place of lodgment for dirt, that would be an annoyance and detract in itself from the desired beauty of the completed battery.

- 10 By using the bracket base plate however, I am enabled to use the same bracket as at the ends and place them in relative position on the opposite ends of the lavatory and both out of view, leaving a clear open space 15 between the lavatories and thus eliminating the fouling space before noted. In fact the only part of the standard seen from above in Fig. 1 when the lavatories are in place is the top of the heads 2 and the top of the 20 pair of base or bracket plates 17 at intermediate points.

The same is true of Fig. 6 except when the pipe support is used, while with the construction in Fig. 7 there is nothing seen of

- 25 the support from above, thus bringing uncleaned lodgment space to the minimum.

The strength of the head and the method of attaching brackets makes it possible to reduce the spread of the standard or support on the floor to narrow proportions, taking all portions of the support out of the way of the user. The plain design adopted gives for ease of cleaning while the small portion of the support visible under the 35 lavatories enhances the beauty of the completed battery.

I do not wish to limit my claims to the particular design shown by the drawings as it is evident that the brackets, the bracket 40 base plates, and the locking coupling for the rods might easily be used with many designs, neither do I desire to be limited in the use of this device to lavatories and wash sinks as it is understood that the ideas, devices and 45 units, severally or in combination can be used to support many fixtures set in battery formation, such as counters, work tables for various trades and the like.

I believe it broadly new with me to design 50 and use a bracket base plate that carries all brackets under the lavatories, except at the ends of a battery where the standards at the ends place them normally. Also broadly new with me to produce a bracket and base 55 plate that supports a plurality of deep apron lavatories, without the use of tie rods between the standards, and my claims are intended to be generic as to these items.

Having thus described my invention, 60 what I claim is:—

1. In combination with a series of standards each having an upwardly extending head; a bracket support secured to the head of the standard intermediate the outermost 65 standards of the series; brackets secured to

said support and to the heads of the outermost standards; and means for securing the standards together.

2. In combination with a series of standards, each having an upwardly extending head; a base plate or bracket support secured to the heads of the standards intermediate the outer standards; a pair of brackets secured to and extending outwardly from the bracket support; a bracket secured to the head of each of the outermost standards; and means for tying the parts together.

3. In combination with a plurality of standards, each having an upwardly extending head presenting a forward face and a shoulder below said face; a bracket support secured to the face of the intermediate standard and bearing on the shoulder, said support extending laterally to each side of the head; brackets secured to said support and to the heads of the outermost standards; and means for securing the standards together.

4. In a support for the purpose described the combination of a standard having an upwardly extending head; a bracket support secured to opposite faces of the head and extending laterally thereof; and a plurality of oppositely extending brackets secured to said support.

5. In a support for the purpose described, the combination of a standard having a head extending upwardly therefrom; a bracket support embracing said head and secured thereto; and a plurality of oppositely disposed brackets secured to said bracket support.

6. In a support for the purpose described, the combination of a standard having an upwardly extending head; a pair of bracket supporting plates secured to opposite sides of said head and extending laterally thereof to each side, said plates being provided with oppositely disposed elongated slots or openings; a plurality of brackets arranged in oppositely disposed pairs on said plates; and bolts extending through said brackets and through the slots in the plates and serving to secure the brackets in their adjusted 115 positions with reference to the plates.

7. In a support for the purpose described, the combination of a plurality of standards; a plurality of brackets secured to and supported by said standards; rods extending from one standard to the next; and locking means for individually securing the rods to the standards.

8. In a support for the purpose described, the combination of a plurality of standards; threaded nipples extending through said standards; a socket secured upon each nipple; tie rods extending from one socket to the oppositely disposed socket; and means for securing said rods to the sockets.

9. In a support for the purpose described, the combination of a series of standards each having a head presenting opposite vertically disposed faces with a shoulder below each face; a pair of bracket supporting elements secured to the heads other than the outermost ones of the series, each element comprising a half hub like section with plates extending laterally to each side thereof, each plate being provided with longitudinally disposed slots; a plurality of pairs of oppositely disposed brackets; bolts securing said brackets to said plates, said bolts passing through the slots aforesaid; a pair of oppositely disposed brackets secured to the head of each of the outermost standards of the series; and means for securing the standards in fixed spaced relation.

10. In a support for the purpose described, the combination of a plurality of

standards having openings formed in the webs thereof; threaded nipples passing freely through said openings; a pair of sockets secured upon the opposite ends of those nipples which pass through the standards intermediate the end standards and adapted to embrace the webs of such intermediate standards; a socket secured upon the innermost end of each nipple mounted in the outermost standards; a nut mounted upon the outer ends of each of said outermost nipples and coacting with the sockets to secure said nipples to the webs; tie-rods extending from one socket to the oppositely-disposed socket; and means for securing said rods to the sockets.

In testimony whereof I have signed my name to this specification.

WINFIELD E. HINSDALE.
